PAIR OF SPECTACLES

Richard L. Huggins, Rochester, N.Y., assignor to Bausch & Lomb Incorporated, Rochester, N.Y., a corporation of New York

Filed May 31, 1963, Ser. No. 75,136

Term of patent 14 years

(Cl. D57—1)

FIG. 1 is a front view of a pair of spectacles showing my new design;

FIG. 2 is a side view of said pair of spectacles taken from the right side of said spectacles as viewed in FIG. 1;

FIG. 3 is a top view of said spectacles with one temple shown broken away for convenience of illustration;

FIG. 4 is a sectional view through the bridge of the spectacles and is taken along the line 4—4 in FIG. 1; and

FIG. 5 is a sectional view through one of the temples and is taken along the line 5—5 in FIG. 2.

The side of the spectacles not shown has substantially the same appearance as the side shown.

I claim:

The ornamental design for a pair of spectacles, substantially as shown and described.
